UNITED STATES PATENT OFFICE.

CARL C. KING, OF WASHINGTON, DISTRICT OF COLUMBIA.

SAFETY-RAZOR.

1,200,427.

Specification of Letters Patent.

Patented Oct. 3, 1916.

Application filed January 3, 1911. Serial No. 600,547.

To all whom it may concern:

Be it known that I, CARL C. KING, a citizen of the United States, residing at Washington, in the District of Columbia, have invented a new and useful Improvement in Safety-Razors, of which the following is a specification.

My invention relates to improvements in safety razors, and more particularly to the character of the handle and guard plates and the shape and position of these members with relation to one another, by which improvements I provide for greater ease in the use of the razor in shaving and for a more desirable safety razor generally.

Another object of the invention is to provide quick and simple means for attaching and detaching the blade and cap plate.

A further object of the invention is to provide a blade and a cap plate so shaped that they will be highly convenient to grasp with the fingers in attaching them to the guard plate or in handling them with other purposes, and thereby also effecting a saving of material in their manufacture.

With these objects in view my invention consists in the novel features of construction, material, and combination of parts hereinafter described and pointed out in the claims.

In the drawing forming a part of this specification: Figure 1 is a side view, partly in section, of a safety razor constructed in accordance with my invention, showing the handle turned to its longitudinal position with reference to the guard and cap plates. Fig. 2 is another side view of a safety razor of slightly modified form constructed in accordance with my invention, the handle and guard plate in this view being integral or rigidly secured to one another at an acute angle with regard to the longitudinal direction of the guard and cap plates. In this view is shown, partly in section, the manner of providing anti-friction roller or ball bearings between the swiveled finger rest and the body of the handle. Fig. 3 is an end view of the construction shown in Fig. 1, with the handle, which is pivoted at 2, turned to assume an acute angle with respect to the transverse direction of the guard and cap plates. This view also shows, partly in section, the manner of connecting the pivoted or swiveled finger rest to the end of the handle. Fig. 4 is a side view of a form of locking spring which may be

used to lock or hold the handle in its several positions of adjustment with respect to the guard plate. Fig. 5 is a detail perspective view of the locking spring shown in Fig. 4. Fig. 6 is a plan view of the under side (or side to which the handle is attached) of the guard plate. Fig. 7 is a plan view of the blade. Fig. 8 is a sectional elevation of the guard plate, blade and cap plate, taken on the line 8-8 of Fig. 1. Fig. 9 is a detail perspective view of the guard plate, blade and cap plate assembled. Fig. 10 is a detail view of one of the pivoted pins which are designed to lock the cap plate, blade and guard plate together. Fig 11 shows the shape of and the manner of cutting the blades from sheet metal so as to economize in the use of metal.

Like reference numerals refer to similar parts throughout the several views.

In carrying out my invention I employ a double-edged guard 6, with guard teeth 12; and a double edged blade 7, and a double-edged cap plate 3, which guard, blade and cap are adapted to be attached together as shown in Figs. 1, 2, 3, 8 and 9, by headed pins, 10, pivoted at 9 to the guard plate 6, movable in a plane at right angles to the plane of the guard plate, and held in normal position by the spring 8, as shown in the sectional view Fig. 8. While I have shown the pivoted pins 10, 10, with substantially round heads, it is obvious that they may be made with a notch, a shoulder, or flange on one or more sides, or may be made in the shape of a latch, and I do not desire to limit myself to the exact construction shown. It is also apparent that a cap plate is not absolutely essential in the construction of my razor, as the headed pins may be of such height and shape as to engage and clamp or hold the blade alone in proper position with relation to the guard without the use of a cap, and I desire that such arrangement be considered as within the scope of my invention.

The headed pins 10 are provided with pivots 9, which fit into the bearings in the guard plate 6, and the said pins have their under ends so shaped that the spring 8 on the under side of the guard plate 6 will bear against the portion 17 of the said headed pins and cause them to press normally against the cap plate and blade when in position, the headed portions of the pins

fitting snugly into the recesses in the ends of the cap plate 3, as shown in Figs. 8 and 9, so as to lock or secure these parts to the guard plate.

5 When it is desired to detach the cap plate and blade from the guard plate, it may be quickly and easily done by pressing the thumb or finger against one end of the cap plate and blade, which may be so constructed 10 as to project slightly beyond the end of the guard plate, when the headed pin at the opposite end of the guard plate will be turned on the pivot 9 sufficiently far to allow the ends of the cap plate and blade 15 so pressed and moved longitudinally on the guard plate to pass the head of the other pivoted pin with but slight resistance. In attaching the blade and cap plate to the guard plate, but little longitudinal pressure 20 or sliding movement of the cap and blade is necessary, as the headed pins are so constructed that the recesses in the end of the cap plate and blade will press the heads of the pivoted pins, 10, 10, backward and allow the blade and cap plate to pass by the 25 heads of the pins, when the blade and cap plate will assume and be held by the headed pins in their proper positions for the use of the razor in shaving. It is also apparent 30 that instead of pivoting both pins, one of them may be mounted rigidly to said guard plate and the other one pivoted so that it may be opened outwardly with the thumb or finger, or by sliding the cap plate as mentioned above, and closed with the finger to engage the recess in the cap plate to hold 35 the parts together.

40 A very important part of my invention is the shape and character of the handle which I provide, as shown in Figs. 1, 2 and 3. This handle is formed with a body portion the upper end of which is provided with a shank or neck 19, terminating in a foot 20, so as to provide for attaching 45 the guard plate to the handle at an acute angle to the general direction of the body thereof, and, while I claim as within the scope of my invention the construction of a razor with the handle integral with the 50 guard plate or rigidly secured thereto at an angle of less than ninety degrees to the general longitudinal direction of the plane of the blade and guard plates as shown in Fig. 2, I preferably construct my razor with 55 the handle pivoted at 2, so that it may, at will, be turned to the position shown in Figs. 1 and 2, or to the position shown in Fig. 3; always, as will be seen, maintaining an acute angle of substantially the same degree with respect to the plane of the blade and guard plate. This construction of the 60 handle in combination with a double-edged guard plate and doubled-edged blade, and with a finger rest on the end of the handle, 65 as shown is a very great improvement, as it

provides a razor handle of such shape as will allow the user of the razor in either adjustment of the handle to at all times see the point of contact of the blade and guard with the skin of the face; the hand 70 grasping the handle being always at such an angle with respect to the blade of the razor as not to interfere with the view of the person using the razor. This construction of the handle also admits of the use of 75 the razor with the handle extending in the longitudinal direction of the blade and guard and in the transverse direction thereof, thus suiting the person accustomed to the use of a razor of either type. The shape 80 of the handle in either adjustment is such as to facilitate the handling of the razor with that sliding stroke in shaving which is considered by many persons as highly desirable; particularly is this true when the 85 handle is adjusted to the position shown in Figs. 1 and 2, and I find that, even without a guard plate, a double edged blade attached to the end of a handle at an oblique angle to a line parallel to the cutting edges of the 90 blade may be used with unusual facility on either side of the face with either hand by one who has had no previous experience in the use of such a razor, and I consider this feature a very important part of my invention. 95

To provide for locking the handle in either of the positions indicated in the drawing (Figs. 1, 2 and 3), I use a spring 5, shown in Figs. 4 and 5, which is attached 100 to the foot end of the handle, 20, next to the spring member 8 on the guard plate. This spring 5 has a lug or pin 13 adapted to fit into one of the holes or indentures 14 in the spring member 8, and thus lock the 105 handle in the position desired. The spring, as is shown, has a finger piece or portion which is adapted to extend along the neck or shank 19 of the handle, which finger piece is pressed to bend the spring and lift 110 the head or lug 13 out of the hole or indenture 14 in the spring member 8 when it is desired to turn the handle to a different position. It is obvious that other simple means of providing a spring to lock the 115 handle may be used and I do not desire to limit myself to the exact construction shown.

The blade 7 I construct with saddle-shaped recesses at its ends and the blades so 120 cut as to secure a material saving in the quantity of metal required in their manufacture. The ends, it will be noted in Figs. 7 and 11, are shaped so that the longitudinal edges of the blades extend up into the recesses in the central portions of the adjacent blades in cutting them from sheet metal. This also provides a blade which is most convenient to handle, as the saddle- or bell-shaped recesses in the ends of the blades are 125 130

very convenient in grasping the blades by their ends with the thumb and finger. It will also be noted that I provide a cap and a guard similarly constructed at their ends 5 for convenience in handling.

For convenience in grasping the razor, I provide the end of the handle with a finger rest, as shown in Figs. 1, 2 and 3, and I preferably connect the finger rest with the handle 10 by a collar 11, fitting over an annular flange or shoulder 15, and attached to the portion 16 of the finger rest, so that the finger rest will rotate. By thus swiveling the finger rest so that it will rotate, the angle of the 15 fingers in grasping the handle may be changed and the finger rest will readily conform to the position to agree with the direction of the fingers, thus greatly facilitating the handling of the razor in shaving. This 20 swiveled finger rest I have claimed in my prior application filed May 26, 1909, Serial Number 498,490, but I desire to claim in this application the manner of connecting the body of the handle and the finger rest with a 25 collar as shown in Figs. 1, 2 and 3, and the providing of anti-friction roller or ball bearings 18 at said pivotal connection as shown in Fig. 2. The said anti-friction bearings are provided by forming a slot or groove in 30 the end of the body portion of the handle 1, and a corresponding slot or groove in the head of the finger rest 16, to act as channels or bearings for the balls or rollers.

What I claim as new and desire to secure 35 by Letters Patent is:

1. A safety razor having a guard plate and a cap plate, one of said plates having spring-actuated locking pins pivoted thereto to swing about said pivots in a plane at 40 right angles to the plane of said plate, and the other plate having recesses adapted to engage the distal ends of said pins to hold the parts together.

2. In a safety razor, a guard plate having 45 combined blade-positioning and blade-holding pins at its ends for engaging the ends of a blade, one of said pins being pivoted to said guard plate with the axis of said pivot lying transversely thereof, and the pin movable in a plane at right angles to the plane of said guard plate, and a handle secured to said guard plate at a fixed oblique angle to the plane of said guard plate.

3. In a safety razor, a holder comprising 55 a cap plate having recessed ends, a guard plate having a pivoted locking pin at one end thereof formed to engage the cap plate at one of its ends and a spring actuating said locking pin, and a pin at the opposite end 60 of said guard plate formed to engage the opposite end of the cap plate to hold the parts together.

4. In a safety razor, a holder comprising a guard plate and a cap plate, one of said plates having headed blade positioning pins, 65 one of said pins being hinged to swing in a plane at right angles to said plate, and the other plate having means engaging the headed ends of said pins to hold the parts together. 70

5. In a safety razor, a guard plate and a cap plate, one of said plates having a swinging latch mounted thereon movable in a plane at right angles to the plane of said plate and engaging a recess in the other of 75 said plates to hold the guard and cap plates together.

6. In a razor, the combination with blade holding means, of a handle comprising a body portion having a flange, a finger rest 80 having a threaded end, and an internally threaded collar adapted to fit over said flange and screw on to the threaded end of said finger rest.

7. In a safety razor, a holder comprising 85 a blade-guard member provided with blade-positioning, blade-holding pins, one of said pins being pivoted to swing in a plane at right angles to the plane of the blade-guard, and a spring co-acting with said pins to aid 90 in swinging and holding them.

8. In a safety razor, a double edged guard plate carrying a pivoted pin at either end thereof midway between the longitudinal edges of the guard plate, a spring adapted to 95 bear upon said pins to actuate same, a blade, a cap plate having its ends formed to engage the free ends of said pins to lock the parts together, and a handle attached to said guard plate and extending at an acute angle to the 100 central longitudinal line of the guard plate.

9. In a safety razor, the combination with blade holding means, of a handle comprising a body portion and an end portion, the body portion having a foot on one end carrying means for attaching it to the blade holder, one of said portions having a flange and the other portion a threaded end, and a threaded collar fitting over said flanged portion and screwing on to the threaded end 105 of the other portion. 110

10. In a safety razor, the combination with a blade holder having a threaded stud, of a handle having a body portion with a neck on one end thereof, terminating in a 115 foot at an acute angle to the axis of the body, and a threaded thumb-nut rotatably mounted on said foot for engaging the stud of the blade holder to attach the handle to the holder.

CARL C. KING.
